H. S. HUNT

ROADWAY

Filed July 8, 1921

Inventor
Horace S. Hunt

Edward N. Page

Attorney

UNITED STATES PATENT OFFICE.

HORACE S. HUNT, OF JACKSON, MICHIGAN.

ROADWAY.

Application filed July 8, 1921. Serial No. 483,182.

To all whom it may concern:

Be it known that I, HORACE S. HUNT, a citizen of the United States, and residing at Jackson, in the county of Jackson and 5 State of Michigan, have invented new and Improved Roadways, of which the following is a specification.

This invention relates to the construction of roadways, and its object is to provide a 10 roadway built up of concrete cross ties and longitudinal girders having reinforcing rods where tension stresses are to be expected, the rods of adjacent girders being united permanently.

15 Another object of this invention is to provide a roadway in which each part shall be of the size necessary to carry a predetermined load and in which each part can be leveled up should any portion of the roadway sink because of improper foundation.

20 A further object of this invention is to provide a reliable roadway at minimum cost.

This invention consists of a series of reinforced concrete cross ties and reinforced 25 concrete girders extending longitudinally of the roadway and having their ends resting on the cross ties, the reinforcements at the ends of adjacent girders being connected together and to the cross ties upon which these 30 ends rest.

It further consists in girders formed with longitudinal seats along their upper edges and in cross slabs resting in these seats so as to constitute permanent roadway surfaces.

35 It also consists in the details of construction illustrated in the accompanying drawing and particularly pointed out in the claims.

In the drawing, Fig. 1 is a transverse 40 section of a roadway. Fig. 2 is a longitudinal section thereof. Fig. 3 is a section on the line 3—3 of Fig. 2. Fig. 4 is a section on the line 4—4 of Fig. 3. Fig. 5 is a longitudinal vertical section of a seat portion 45 of a cross tie.

Similar reference characters refer to like parts throughout the several views.

Concrete roadways are usually slabs of 50 substantially even thickness, the plastic material being spread over the sub-grade which is usually of very uneven load-supporting capacity. The waste of concrete is very great and the roadways crack because these slabs are unevenly supported. In the present construction, good and sufficient founda-

tions are easily prepared and the necessary strength of each separate unit is easily provided as the loads thereon can be computed.

The sub-grade of this roadway is preferably scraped so its character can be accurately determined. Trenches for the cross ties 1 are then dug across the roadways, and, if desired, drain tiles (not shown) may be placed in the bottom of each trench to keep it dry. This permits the foundation for 60 each cross tie to be properly prepared and it also permits each cross tie to be properly leveled. While I prefer each of the units of this roadway to be pre-cast at a suitable and convenient location, these units may all 65 be cast in situ.

The cross ties 1 are preferably formed with longitudinal reinforcing rods 2 and 3 of proper size and number, to be estimated by any competent engineer according to the 70 loads to be carried, and I also use stirrups 4 whose loops extend up above the seats 5 formed in these ties.

Extending longitudinally of the roadway 75 and having their ends resting on these seats 5 of the cross ties are the girders or wheel ways 6 which have reinforcing bars 7 near their lower sides and also have pockets or recesses 8 in their ends near their lower sides, the ends 9 of these reinforcing bars 80 being bent, preferably at right angles, adjacent the upper ends of the stirrups 4. The walls 5^a at the ends of these recesses position and limit the lateral movements of the ends 85 of the girders 6. I prefer to form one end 90 of each girder with a sprue 10 through which cast iron may be poured to fill the recesses 8 in the ends of the girders around the bent ends of the reinforcing bars 7 and the stirrups 4. The ends 11 of the spaces between 95 adjacent girders may be closed with sand or clay to prevent the iron 12 which is provided by a portable furnace and poured into the recess 8 from flowing out. The iron unites the ends of the girders and while it 100 permits the cross ties and girders to be leveled should they settle, it prevents all undesirable movement between them.

When the traffic is not excessive, the spaces 105 between the girders 6 may be filled with broken stone, gravel or earth, and the girders will serve as wheel ways for the heavier vehicles. But where the traffic is heavy, roadway slabs 14 of reinforced concrete may be laid across between adjacent girders, these 110

being formed with longitudinal seats or shoulders 13 to support these slabs. The rods 15 at the bottom of the slabs may be of any desired size and number. These slabs 5 may be lifted out to permit the cross ties and girders to be leveled.

The cross ties may be formed with drain passages 16 having side openings 17 and the girders 6 may be formed with the longitudinal holes 18 to receive lighting, telegraph 10 and telephone wires.

The details of construction and proportions of the parts may all be changed by those skilled in the art without departing 15 from the spirit of my invention as set forth in the following claims.

I claim:

1. A roadway consisting of reinforced concrete girders and reinforced concrete girders 20 cross ties extending across beneath the girders and supporting them, means to unite the ends of the girders to each other and to the cross ties, and transverse slabs resting on the girders.
2. A roadway consisting of a plurality of longitudinal wheel ways of reinforced concrete each made up of separate sections, concrete cross ties extending across beneath the wheel ways and supporting the ends of the 30 sections, and roadway material between the wheel ways.
3. A roadway consisting of a plurality of longitudinal wheel ways, each made up of separate sections of reinforced concrete having 35 recesses in their ends into which the ends of the reinforcements extend, concrete cross ties supporting the ends of said sections and stirrups extending from the cross ties up into the said recesses, and metal filling the re-

cesses around said reinforcements and stirrups.

4. A roadway consisting of a plurality of longitudinal wheel ways of reinforced concrete each made up of separate sections, concrete cross ties extending across beneath the 45 wheel ways and supporting the ends of the sections, and roadway material between the wheel ways, said cross ties being formed with longitudinal drainage passages.

5. A roadway consisting of a plurality of longitudinal wheel ways of reinforced concrete each made up of separate sections, concrete cross ties extending across beneath the wheel ways and supporting the ends of the 55 sections, and roadway material between the wheel ways, said wheel ways being formed with longitudinal passages to receive wires.

6. A roadway consisting of a plurality of longitudinal wheel ways of reinforced concrete each made up of separate sections, concrete cross ties extending across beneath the wheel ways and supporting the ends of the sections, and roadway material between the 60 wheel ways, the upper sides of the cross ties being formed with depressed seats whose side walls restrict lateral movement of the 65 wheel ways.

7. A roadway consisting of reinforced concrete cross ties extending across the roadway, reinforced concrete girder sections resting thereon and constituting wheel ways and provided with longitudinal seats along their 70 edges below their upper surfaces, and roadway slabs resting on said seats and constituting a roadway in connection with said 75 girders.

HORACE S. HUNT.
